REFINING MINERAL OIL WITH SOLVENTS

Richard Jewell Dearborn, Summit, N. J., assignor to The Texas Company, New York, N. Y., a corporation of Delaware

No Drawing. Application October 24, 1932,
Serial No. 639,299

2 Claims. (Cl. 196—13)

This invention relates to the refining of mineral oils and more particularly to refining petroleum hydrocarbons by solvent extraction.

The invention broadly contemplates refining mineral oil to remove impurities and undesired components by extracting the oil with a selective solvent in the presence of a liquid material which, when mixed with the oil, renders it more susceptible to extraction with the solvent.

10 More specifically, the invention contemplates extracting the oil with a selective solvent, such as liquid sulphur dioxide, furfural, nitrobenzene, and the like, in the presence of, or in admixture with, a light low-boiling and relatively non-viscous liquid material such as a light hydrocarbon liquid adapted to dissolve the oil or the desired components thereof and precipitate the tarry bodies.

A light hydrocarbon precipitating liquid suitable for the purpose of my invention may comprise natural gasoline or light petroleum naphtha fractions, or the essential constituents of such light gasoline or naphtha as, for example, propane, propylene, butane, and the like. In general, it is advantageous to use a light petroleum fraction having a lower boiling range than the naphtha more commonly used as a solvent or diluent, for example, in dewaxing operations of the prior art.

30 Light aromatic hydrocarbon materials may also be employed equally as well as the paraffin hydrocarbons, and it is contemplated that other liquids which are adapted to dissolve the oil, or are miscible therewith, and which tend to precipitate the undesired asphaltic or tarry bodies, may be employed in the practice of my invention.

According to my invention, the oil to be treated is mixed with a light liquid material, for example, of the nature of propane or butane, which is adapted to dissolve the desirable components of the oil but which tends to precipitate the undesired constituents, such as the unsaturated and tarry bodies. These undesired constituents 40 may be partially precipitated, or their solubility in the mixture may be so greatly decreased, that they are in a state of incipient precipitation and are, therefore, more readily extracted and separated by the solvent. The oil undergoing treatment is thus rendered more susceptible to treatment by the solvent liquid and the extraction of the undesired constituents of the oil is greatly facilitated and accomplished more effectively.

Light hydrocarbons of the nature of propane 50 or butane are of advantage in this connection

since they are substantially completely miscible with the oil fractions derived from crude petroleum, and, upon mixing with oils of this nature containing asphaltic or tarry bodies, they effect a substantial precipitation of these tarry bodies. 5 These precipitated constituents, which may tend to remain suspended in the oil, are thus more readily dissolved by the liquid sulphur dioxide, furfural, or other solvent liquid used.

The treatment with the solvent liquid may 10 follow the mixing of the oil with a light hydrocarbon material, or it may be carried out simultaneously with such mixing. The light hydrocarbon material and solvent liquid may be mixed with or added simultaneously to the oil, or they 15 may be first mixed together and the resulting admixture commingled with the oil to be treated.

My invention is well adapted, for example, to the manufacture of lubricating oils. Lubricating oil fractions usually contain objectionable 20 constituents in the form of aromatic and unsaturated bodies which are readily oxidizable, as well as sulphur-bearing bodies. These objectionable constituents may be largely in the form of tarry constituents which, as mentioned 25 above, are more readily extracted from the oil in the presence of a light liquid of the nature of propane or butane.

At the same time, during this solvent treatment, the naphthenic or low viscosity index constituents 30 of the oil may be extracted so that, by the practice of my invention, I am able to prepare stable lubricating oil fractions of high viscosity index and free from unstable and other objectionable constituents.

In carrying out the invention in connection 35 with the extraction of lubricating oils, the lubricating oil fraction may be mixed or dissolved in about an equal proportion of the light petroleum fraction. The proportions used may be either 40 greater or less, depending upon the nature of the oil undergoing treatment. This mixture is then mixed with furfural or liquid sulphur dioxide in the proportion of about one part of dilute oil to one part of selective solvent. Here again, the 45 proportions may be varied, depending upon the nature of the oil undergoing treatment and the degree of extraction desired.

The mixture is then allowed to settle into two 50 layers, the lower layer comprising the dissolved low viscosity index and other undesired bodies, while the upper layer comprises the purified oil of relatively high viscosity index. These layers are separately withdrawn and the solvent liquid 55

and light low-boiling material recovered for further use.

The treatment may be carried out at any temperature or pressure desired. The temperatures used may range from considerably below normal room temperature to 200° F. or more. The pressure should be adjusted, depending upon the volatility of the light hydrocarbon or other liquid precipitant used, so as to maintain the latter in a substantially liquefied state during the extraction. Where it is desired to carry out the treatment at low temperatures, an excess quantity of the volatile precipitant liquid may be added to the oil, or the mixture of oil and solvent undergoing treatment, and be refrigeratively evaporated therefrom in order to produce such cooling.

In connection with the extraction of wax-bearing oil, the extraction treatment of my invention may either precede or follow the dewaxing step. It is also contemplated that the dewaxing and extracting steps may be combined using the extracting solvent and light hydrocarbon liquid mixture as a combined dewaxing and extracting medium. By properly adjusting the liquid proportions and carrying on the procedure at temperatures of around 0° F., or at which congelation of the wax occurs, it is possible to separate the tarry matter as well as the wax in substantially the same operation.

The invention is not necessarily limited to the treatment of lubricating oil fractions but may also be adapted to the refining and purification of various hydrocarbon or mineral oil fractions, including naphtha, kerosene, etc., as well as various residual or distillate fractions or products derived from petroleum or other sources. It is

also applicable to the treatment and purification of the crude petroleum itself.

Obviously many modifications and variations of the invention, as hereinbefore set forth, may be made without departing from the spirit and scope thereof, and therefore only such limitations should be imposed as are indicated in the appended claims.

I claim:

1. In the treatment of wax-bearing mineral lubricating oil containing asphaltic bodies, the method of simultaneously removing asphaltic bodies and wax constituents comprising mixing the oil with a light petroleum fraction comprising mainly hydrocarbons having anti-solvent properties for asphalt characteristic of propane and a wax anti-solvent liquid comprising liquid sulphur dioxide in proportions such that at a temperature of the order of 0° F. asphaltic bodies and wax constituents are precipitated from the cold mixture, cooling the mixture to a temperature of the order of 0° F. to precipitate said asphalt and wax, and removing the precipitated material therefrom. 15

2. In the treatment of wax-bearing mineral lubricating oil containing asphaltic bodies, the method of simultaneously removing asphaltic bodies and wax constituents comprising mixing the oil with propane and liquid sulphur dioxide in proportions such that at a temperature of the order of 0° F. asphaltic bodies and wax constituents are precipitated from the cold mixture, cooling the mixture to a temperature of the order of 0° F. to precipitate said asphalt and wax, and removing the precipitated material therefrom. 25

R. J. DEARBORN. 35
